Inventor:

Robert Edwin Reardon

UNITED STATES PATENT OFFICE.

ROBERT EDWIN REARDON, OF COLUMBIA, PENNSYLVANIA.

TOY-PISTOL BODY.

Application filed February 18, 1924. Serial No. 693,548.

To all whom it may concern:

Be it known that I, ROBERT EDWIN REARDON, a subject of the King of Great Britain, residing in the town of Columbia, county 5 of Lancaster, and State of Pennsylvania, United States of America, have invented a new and useful Toy-Pistol Body, of which the following is a specification.

My invention relates to improvements in 10 means for assembling metal toys, particularly iron toy pistols and the like, whether cast or formed otherwise, by so forming integrantly of their substance certain component parts of the article that they lock fast 15 to each other when pressed together, by virtue of such elasticity as may be inherent in their substance. The use of my improvement, therefore, dispenses with the common use of rivets, bolts, screws and other extraneous means of holding assembled the component parts of such devices, the employment of which adds considerably to the cost 20 of manufacture. My method of making assembling means integral with component parts, taking advantage as far as practicable 25 of the inherent elasticity of the substance of such parts contributes materially to lessen the labor, time and equipment usually required for the production of articles of the type to which my improvement 30 may be applied.

I attain the object of my invention by varied adaptations of the means to the articles to which it may be applied and I illustrate 35 herein its application to a certain design of toy pistol, by the construction, combination and arrangement of parts hereinafter described and particularly pointed out in the claims. It is understood that I do not intend to limit myself to the details of construction or combination of the various 40 parts as shown and described herein.

My invention is illustrated in the accompanying drawings in which:

Figure 1 is a left side view, slightly in perspective from the lower and front sides, of a toy pistol body comprised of right and left halves and a door plate that is pivotally mounted therebetween, the said door plate being depicted as swung open to show the means by which the body halves are secured together.

Figure 2 is an interior side elevation of the left half of the toy pistol body.

Figure 3 is an exterior view of the right 55 half of the toy pistol body, slightly in perspective from the front end.

Figure 4 is a fragmentary view of parts of the left and right sides of the toy pistol body, illustrating a modification of the 60 construction of the body assembling means as shown in Figure 1.

In the drawings like numerals indicate similar parts.

The left side A of the toy pistol as here- 65 in shown has an opening A¹ in it over which projects a lug A² that preferably tapers upwardly from said opening A¹ towards side B of the pistol body. The under side of said lug A² which overhangs opening A¹, 70 preferably has a slight downward marginal projection at its forward extremity, A⁶. At another part of the pistol side A another lug, as A³, projects over another opening in pistol side A, or cut away section of same 75 that is equivalent to an opening. On a pivotal post A⁴ of the side A the door plate C may be rotatably mounted by means of its flange C¹ and hole C² therein. Usual means for preventing lateral displacement of the 80 pistol halves when joined are provided by the interlocking effect of projections such as B⁷ and B⁸ on side B entering corresponding recesses on the opposite half, such as A⁷ and A⁸ on side A. The pistol side B has a de- 85 pressed or loop section B⁹ at its forward end which when assembled coincides in plane with side A and completes said side underneath the lug projection A³ of same, being adapted to fit thereunder and engage the 90 said lug A³. An assembling arm B¹ is ex- 95 tended in the pistol side B, in the plane thereof or parallel thereto, and bent downward terminally, towards the location of lug A² in side A, to form a step B² with a recess B⁶ therein formed by a raised margin on said step B² that abuts the tapered upper edge of lug A² when the pistol halves are 100 opposed for joining, the recess B⁶ being adapted to engage the marginally depressed nose A⁶ of said lug A² when the pistol is assembled. The assembling arm B¹ by its for- 105 mation, length and relation to the body of pistol side B is limitedly resilient, even though it may be of substance that is frangible. When the pistol sides A and B are joint- 110 ingly opposed to each other the arm B¹ lies in such relation to lug A² of side A that the

step B² slidingly rests upon the sloped side or edge of said lug A², in position to slide down said slope into the opening A¹ below.

The operation of assembling the pistol body and effecting this application of my assembling means is as follows: The door plate C being placed in position on pivot post A⁴ of pistol side A by means of hole C² in flange C¹, in open position as shown in Figure 1, the depressed or loop section B³ of pistol side B is passed into place under the lug projection A³ of side A, thereby engaging said lug A³ and preliminarily locking together the forward ends of sides A and B. The step B² of arm B¹ of side B is then forced down the sloped side of lug projection A² of side A, by pressure on arm B¹, until the said step B² rides clear of the nose A⁶ of said lug A² and springs back laterally and upwardly underneath the said lug A² into tight engagement with same, the nose A⁶ of the lug incidentally making said engagement still more positive by engaging with recess B⁶ of the step B². The depressed or loop section B³ of pistol side B is simultaneously drawn into tight engagement with the lug projection A³ of pistol side A, thus completing a tight and positive assembly of the pistol body.

In the modified form of the application of my assembling means herein described, which is shown in Figure 4, the locking engagement of the pistol sides A and B is effected by a forked form of assembly arm B¹, another arm B⁴ being added thereto, both of said arms being stepped, having step ends B² and B⁵, laterally opposed to and spaced from each other and adapted to be forced, by pressure on the arms B¹ and B⁴, down between the opposed sloped sides of projected lugs A² and A⁵ overhanging a larger opening A¹ in pistol side A, until the said arms B¹ and B⁴, forced towards each other laterally by such downward pressure, ride clear of the bottom of lugs A² and A⁵, in opening A¹, and expand under said lugs and spring upward into tight engagement with them. This construction of the assembly arm of side B dispenses with the lug projection A³ of side A, shown in Figures 1 and 2.

It is possible to contrive many other modifications and adaptations of my method of lock joining component parts of iron and other metal toys and the like by making the joining means integral with some of said parts and so utilizing the inherent resiliency of the substance of which said parts are made.

I claim:

1. In a toy pistol having a plurality of component body parts, continuously reusable automatically effective means integrant with component parts for completely securing together all the component parts.

2. In a toy pistol having a plurality of component parts made of frangible metal, reusable means integrant with said parts for permanently or temporarily assembling together all the component parts.

3. In a toy firearm body having molded component parts manually operable continuously reusable automatically effective means integrant with certain of such component parts whereby all of the component parts may be completely assembled together.

4. In a toy firearm body having a plurality of parts, component parts, manually operable reusable means formed integrantly of certain of said component parts and adapted by formation and inherent resiliency of substance to securely yet detachably interlock together when joined a plurality of said component parts of said body and thereby assemble permanently or temporarily all the component parts thereof.

5. In a molded metal toy pistol body having a plurality of component parts, continuously reusable means integrant with certain of said component parts and automatically effective by assembly to cause interengagement of said parts.

6. In a frangible metal toy firearm having a casing comprised of a plurality of parts, such opposed yielding and engaging formation of certain of such constituent parts that they rigidly interlock with each other when joined yet are continuously intactly reusable.

ROBERT EDWIN REARDON.
